[57] CLAIM

The ornamental design for a display case for a baseball and bat, as shown and described.

DESCRIPTION

FIG. 1 is a top, front, and right side perspective view of a display case for a baseball and bat showing my new design; FIG. 2 is a bottom, rear and left side perspective view thereof;

FIG. 3 is an enlarged right side elevational view thereof; FIG. 4 is a top, front and right side perspective view of a second embodiment of a display case for a baseball and bat showing my new design;

FIG. 5 is a bottom, rear; and left side perspective view thereof; and,

FIG. 6 is an enlarged right side elevational view thereof. The broken-line disclosure of a baseball and bat in the views is for illustrative purposes only and forms no part of the claimed design.
